OBTURATOR

Joseph L. Gillman, Jr., United States Navy

Filed May 31, 1945, Ser. No. 596,931

1 Claim. (Cl. 89—26)

This invention relates to an obturator or gasket, and more particularly to a stable unitary gas check pad for use in connection with breech loading ordnance or other equipment utilizing high fluid pressures.

Previously, it has been common practice to form obturators or gas check pads of a plurality of mass of heat resistant discs or fibers of asbestos variously oriented, impregnated or bound with vegetable, mineral or animal oils, fats or waxes, natural or processed, and the combined mass jacketed with metal gauze or fiber cloth. However, practice has proven these pads to have relatively poor durability, particularly under conditions of prolonged or rapid fire, due to a decrease in thickness of the pad brought about by the exudation of the impregnating or binding material or due to a rupture of the gasket by the steel gas check rings.

The primary object of this invention is to provide an unjacketed unitary obturator or gasket which embodies the well-known desirable characteristics such as, resilience, high tensile strength, resistance to abrasion, resistance to the action of oil and water, chemical stability and freedom from exudation or diminution in volume at high and low temperatures and at high and low pressures, in which the lateral or diametrical thermal coefficient of expansion is approximately that of the material enduring the pressure against which it seals.

An obturator or gasket made in accordance with this invention comprises multiple, transverse layers of a flexible fabric having a high tensile strength and low coefficient of thermal expansion, and a thermally stable rubber-like material, which impregnates and coats the fabric and bonds the layers together into a unitary structure. In a preferred form, the obturator or gas check pad is constructed of a series of chloroprene (neoprene) impregnated and covered glass cloth discs of suitable diameters set one upon the other, molded under pressure, and cured with heat in steel molds to produce a completely bonded unit of a pre-designed size and shape.

A further explanation appears in the specification to follow, accompanied by the drawing in which:

Figure 1 is a cross-sectional view of the obturator interposed between a mushroom and a breech plug of a breech mechanism.

Figure 2 is a cross-sectional view of part of the bonded gas check pad.

Figure 3 is a perspective view, partly in cross-section, of a neoprene composition impregnated and coated glass cloth disc.

Referring to the drawing, Figure 1, A represents the gun, B the breech plug, C the mushroom retained in position by means of nut D which is attached to the mushroom stem and seated against spring E. The purpose of the spring is to resiliently position the mushroom against the obturator and forward gas check ring thereby permitting a variation in the longitudinal thickness of the obturator. The mushroom and stem are provided with a passage G through which the charge in the chamber F is fired in any suitable manner.

2

The obturator is interposed between the conventional mushroom and the breech plug in such a way as to transmit the firing load from the mushroom to the breech plug, and is thereby distended laterally to provide a gas seal at the gas check seat H and at the rear base of the mushroom without interfering with the operation of the breech mechanism.

The obturator 10, as shown, is in the form of an annulus through which the mushroom stem may extend, 10 the obturator having its outer surface 11 beveled to fit closely against the gas check seat H. The rear face 12 is flat and fits closely against the front end of the breech plug B, while the forward face 13 of the obturator is a conical form to receive the base of the mushroom seat. 15 At its outer edges, the obturator is beveled, as shown at 14 and 14-A, to provide annular recesses at the ends of the obturator for receiving suitable gas check rings, (not shown), if such rings are desired.

The obturator comprises a plurality of laminations of 20 a flexible, plastic-coated material having a high tensile strength and a low diametrical coefficient of thermal expansion. More particularly, each lamination 15 as shown in Figure 3, includes a layer of fiber glass cloth, or the like, having strands 16 of high tensile strength and low 25 thermal coefficient of expansion extending generally transversely to the obturator, (that is, laterally with respect to the mushroom stem). The fiber strands 16 are coated and impregnated with a plastic material 17 which has rubber-like qualities, such as a neoprene composition. 30 In the preferred construction, each strand 16 is made up a plurality of fibers, so that when the neoprene composition 17 is applied to the glass cloth the strands themselves are impregnated, bonded and coated by the neoprene composition which extends continuously over 35 the two faces of the cloth and from face to face through the interstices of the fabric.

The laminations 15 are superimposed and molded together under pressure and heat to produce a completely 40 bonded unit of the desired form. It will be understood that the several laminations 15 may be of varying diameters, as shown, to provide the obturator with the desired shape.

With the new construction, the obturator is extremely 45 resistant to transverse or lateral expansion under heat and its resistance in this respect is much greater than its resistance to longitudinal expansion. This is so because the transverse strands 16, being of high tensile strength and low thermal coefficient of expansion, prevent any substantial transverse expansion of the laminations 15. 50 The spaced layers of glass cloth 16 serve to reinforce or bind the neoprene composition 17 and because of their intimate association with the neoprene composition act to resist to a high degree any tendency for the obturator to expand transversely to a greater extent than the gun 55 itself and thereby cause binding against the gas check seat H, or upon decreasing temperatures to shrink more than the gun and hence fail to form a gas seal. As pointed out above, the obturator 10 has less resistance to longitudinal expansion than to lateral or transverse expansion, because of the disposition of strands 16. On the other hand, any tendency of the obturator to expand longitudinally is accommodated by the spring E.

The new obturator is extremely resistant to wear, is 60 resilient and flexible so that it can readily adapt itself to service requirements, is impervious to oil and water, and may be easily molded.

Tests conducted on an obturator made in accordance 65 with the specification appurtenant to this invention disclosed that in the course of a 355° F. change in temperature, the thickness varied .066"; the diameter varying .013". In other words, the diametrical thermal co-

efficient is equal to .0000051 inch per inch per degree Fahrenheit, which is similar to the diametrical thermal coefficient of the gun. The thickness coefficient is equal to .00016 inch per inch per degree Fahrenheit.

Maximum temperature and oil immersion tests have proven similarly satisfactory.

It will be apparent that variations in the thermal coefficient of expansion may be effected by using different materials in the fabric 16 or the bonding 17, or both, or by varying the ratio of the total fabric thickness to the total bonding thickness.

The invention herein described may be manufactured and used by or for the Government of the United States of America for governmental purposes without the payment of any royalties thereon or therefor.

Having thus described my invention in the foregoing specification, I claim:

In a breech mechanism for closing and sealing the chamber of a gun having a gas-check seat formed of a surface of revolution with predetermined thermal coefficient of expansion, a substantially cylindrical composite pad having an outer peripheral surface adapted to engage said seat throughout its inner periphery, a breech plug having a plane backing surface immediately

adjacent said pad, a mushroom positioned on the side of said pad opposite said breech plug with a conforming surface confronting the forwardly facing lateral surface of said pad, said mushroom having limited freedom of movement axially of said seat for transmitting fluid pressure in said chamber throughout the lateral surface of said pad, said pad being comprised of alternate bonded layers of resilient and fibrous material wherein said layers are positioned normal to the direction of movement of said mushroom whereby said resilient material will obturate between the layers of fibrous material to engage the peripheral surface of said seat when said pad is compressed between said breech plug and said mushroom by the application of fluid pressure to said mushroom.
